UNITED STATES PATENT OFFICE.

EARLE L. KELZER, OF CATELLA, DISTRICT OF ALASKA, AND WESLEY P. RODGERS, OF SEATTLE, WASHINGTON.

INDICATOR.

No. 858,606.

Specification of Letters Patent.

Patented July 2, 1907.

Application filed March 1, 1907. Serial No. 360,121.

To all whom it may concern:

Be it known that we, EARLE L. KELZER and WESLEY P. RODGERS, citizens of the United States of America, and residents, respectively, of Catella, Alaska, and of 5 the city of Seattle, in the county of King and State of Washington, have invented certain new and useful Improvements in Indicators, of which the following is a specification.

Our invention relates to improvements in indicators 10 for elevators and has for its primary object the provision of an improvement of this nature through the medium of which the passengers of an elevator car can make known to the operator or conductor the floors to which they desire to be conveyed, without calling out 15 the number of each floor as now practiced.

A further object is to provide an improvement of the type indicated which will be comparatively simple in construction, embracing but few parts which are not liable to readily get out of order, and very efficient in 20 operation.

Referring now to the accompanying drawings in which like numerals of reference indicate like parts throughout the several views: Figure 1 is a sectional view showing an elevator shaft and a car therein. Fig. 25 2 is a section taken on line 2 of Fig. 1. Fig. 3 is a fragmentary perspective view of a portion of the car, showing more particularly the interior thereof. Fig. 4 is a fragmentary view in perspective taken from the exterior of the car and illustrating the arrangement of the 30 cam pieces of the indicator. Fig. 5 is a view in front elevation of the indicator, a portion of the front wall thereof being broken away. Fig. 6 is an end view of the indicator one of the walls thereof being removed and the front wall shown in section. Fig. 7 is a sectional 35 view taken on line 7—7 of Fig. 6. Fig. 8 is a diagrammatical view of the wiring employed, and Fig. 9 is a detail view on enlarged scale showing a slightly modified construction of strike lug or abutment.

Reference numeral 1 indicates the elevator shaft, 2 40 the car therin, and 3, 3' and 3'', the second, third and fourth stories of the building. The indicator shown, indicated by numeral 4, being designed for a four story building, but, as is obvious, the number of floors is not important to the invention.

45 The indicator 4 is preferably arranged at a suitable point in the elevator where it can be readily seen by the operator and comprises a suitable casing having its front wall provided with glass panels 5 which are numbered as shown in Fig. 5 to indicate the various floors.

50 Reference numeral 6 indicates partitions which extend rearwardly from between the glass panels 5 and serve to prevent the light from a lamp 7 shining through any more than that glass panel directly in front thereof.

Reference numeral 8 indicates the generator which 55 supplies the lamp circuits and 9 a battery or generator which supplies the push button circuits for closing the lamp circuits.

Each lamp 7 is in an independent circuit as clearly shown in Fig. 8 in which A and B indicates the lead 60 wires and, a, b, the branch wires of one circuit, a', b' the branch wires of the second circuit and a'', b'' the branch wires of the third circuit. Each lamp circuit is provided with a circuit closer, as 10, fulcrumed by a pin 11 in the indicator casing (see Fig. 6) and having its upper portion extended so as to lie opposite an electro-magnet 12 and form the armature thereof. The electro-magnets are each in independent circuits provided with push buttons 14.

Push buttons 14 are arranged in the car where they 70 can be readily reached and operated by entering passengers. Thus assuming that a passenger presses one of the buttons 14, this will close the circuit in which it is included, thereby energizing its electro-magnet 12 and causing the latter to attract its armature whereby 75 the lamp circuit with whose closer said armature is associated will be closed and the lamp lighted.

The lamp circuit opening devices are identical and a description of one will therefore suffice, this comprises a push rod 15 slidably supported in the indicator casing 80 and having one end portion projecting therefrom and provided with a cam 16. The main end portion of this push rod is positioned so as to strike the adjacent armature and force it to the position shown in Fig. 6, when said push rod is forced inwardly by reason of its cam 85 striking on abutment or strike lug 17, fixed to the wall of the elevator shaft. Spring 15' returns push rod 15 to its normal position after each operation thereof.

Abutments or strike lugs 17 are fixed to the wall of the elevator shaft opposite each floor, the same being 90 arranged out of vertical alinement so that there will be but one lying in the path of a respective cam 16.

In Fig. 9, the strike lug or abutment 17' shown is supported on a rod 18, which can be secured to the wall of the elevator shaft in any desired manner, for vertical 95 adjustment.

While we have herein disclosed push buttons 14, any other form of circuit make and break means can be employed as found desirable without departing from the spirit of our invention.

Having thus described our invention, what we claim as new and desire to secure by Letters Patent of the United States of America, is:—

1. The combination with an elevator shaft and the car 100 therein, a signal lamp in said car, a circuit in which said lamp is included, a circuit closer included in said circuit and arranged on said car, and means operated by and during movement of said car for operating said circuit closer to open said circuit. 105

2. The combination with an elevator shaft and the car therein, a signal lamp in said car, a circuit in which said lamp is included, a circuit closer included in said circuit and being arranged on the car, an abutment on the wall 5 of said elevator shaft and means operated by said abutment for opening said circuit.
3. The combination with an elevator shaft and the car therein, a signal lamp in said car, a circuit in which said lamp is included, a circuit closer included in said circuit, 10 electro-magnetic means for operating said circuit closer to close said circuit, an abutment on the wall of the elevator shaft, and means operated by said abutment for opening said circuit.
4. The combination with an elevator shaft and the car 15 therein, a signal lamp in said car, a circuit in which said lamp is included, a circuit closer included in said circuit, an electro-magnet for operating said circuit closer to close said circuit, a circuit in which said electro-magnet is included, a circuit closer for said last named circuit arranged on said car, and means operated during movement 20 of said car for operating said first circuit closer to open said first circuit.
5. The combination with an elevator shaft and the car 25 therein, a signal lamp in said car, a circuit in which said lamp is included, a circuit closer included in said circuit and arranged on said car, means for effecting the operation of said circuit closer to close said circuit, and means operated by and during movement of said car for operating said circuit closer to open said circuit.
- 30 6. The combination with an elevator shaft and the car therein, of a plurality of electric circuits each having a signal lamp included therein arranged on said car, a circuit closer included in each of said circuits, abutment means on the wall of said elevator shaft, and means operated by said abutment means for operating said circuit closer to open said circuit closer.
7. The combination with an elevator shaft and the car therein, a signal lamp, a circuit in which said lamp is included, a circuit closer included in said circuit, an electro-magnet, said circuit closer being pivoted intermediate 40 its ends and having one end portion arranged adjacent said electro-magnet and adapted to be attracted thereby, a circuit in which said electro-magnet is included, a push button on the car for closing said last named circuit, and means for operating said circuit closer for opening said 45 first named circuit.
8. The combination with an elevator shaft and the car therein, a plurality of signal lamps, a plurality of electric circuits each having one of said lamps included therein, a circuit closer in each of said circuits, electro-magnets 50 having armatures carried by said circuit closers, abutments on the wall of said elevator shaft, means operated by said abutments for moving the armatures away from said electro-magnets, a plurality of circuits on said car each having one of said electro-magnets included therein, and a circuit closer in each of said last named circuits arranged 55 to be operated by a person on said car, for the purpose specified.

Signed at Catella, Alaska this 28th day of January 1907.
